J. S. THOMPSON

BRAKE SHOE MOLD

Filed July 20, 1923

24 1830 Inventor: 10
James S. Thompson
By: Wm O. Bell Atty.

UNITED STATES PATENT OFFICE.

JAMES S. THOMPSON, OF PELHAM, NEW YORK.

BRAKE-SHOE MOLD.

Application filed July 20, 1923. Serial No. 652,774.

To all whom it may concern:

Be it known that I, JAMES S. THOMPSON, a citizen of the United States, residing at Pelham, in the county of Westchester and State of New York, have invented certain new and useful Improvements in Brake-Shoe Molds, of which the following is a specification.

This invention relates to the manufacture of brake shoes without chilling, and its object is broadly to facilitate the manufacture of such brake shoes in permanent molds by the provision of means for preventing any chilling effect upon the shoe casting from the metal of the mold, and at the same time providing a mold in which the parts to be embedded therein can be easily inserted and supported in position, and which can be readily and quickly opened and closed so that the casting operation may be speedily and economically performed.

In the accompanying drawing illustrating a selected embodiment of the invention—

Fig. 1 is a central sectional view on the line 1—1 of Fig. 2.

Fig. 2 shows the mold of Fig. 1 partly in elevation and partly in longitudinal section.

Fig. 3 is a horizontal sectional view on the line 3—3 of Fig. 2.

Referring to the drawing, the mold comprises a drag member 6 and a cope comprising a relatively fixed member 7 and a slidable member 8. The drag is hinged at 9 to the fixed member 7 of the cope and is adapted to swing freely down from the cope as indicated in broken lines in Fig. 1. The cope member 8 is provided with ears 10 bored to receive the guide bars 11 mounted on the fixed member 7 of the cope and projecting forward to support the member 8 of the cope and its sliding movement to and from closed position with relation to the other members of the mold. The drag member has one or more tongues 12 which are adapted to be secured in slotted keepers 13 by removable pins 14 to hold the drag in closed position against the cope. One or more clamping bars 15 is pivotally secured to the fixed member 7 of the cope at 16 and carries a set screw 17 at its free end to engage the slidable member of the cope for holding the slidable member in proper relation to the fixed member of the cope during the casting operation. When the mold is closed the two members of the cope will be held rigidly clamped together and the drag

member will be held rigid in its proper relation to the cope.

The parting line between the two members of the cope extends longitudinally of the mold and substantially central of the mold cavity 18, which is formed in the construction illustrated, almost entirely in the cope. A part of the mold cavity is located in one cope member and a part in the other cope member, and there is also an opening 19 of substantial size extending through the cope and communicating with the mold cavity, a part of this opening being in one member and a part in the other member of the cope. A sand plug 20 preferably carried by a holder 21 fits snugly in the opening 19 and it is provided with a recess 22 to form the attaching lug of the shoe casting. Looped wires 23 are embedded in the sand core with their ends projecting beyond the bottom thereof to enter the mold cavity for engagement with the reinforcing back 24 to suspend said back and the attaching lug 25 and the core 26 for forming the opening within the mold cavity preliminary to closing the mold and during the casting operation. A support 27 or other suitable means is engaged with the looped portions of the wire and with the top of the plug to retain the wires in proper place.

The foregoing structure is more particularly described in my co-pending application Serial No. 652,773, filed July 20, 1923, and need not be described here with greater particularity.

In that application I have shown and described a mold constructed for the manufacture of integral composite brake shoes having chilled sections produced by the chilling effect of the members of the metal mold, but in this application I have shown a mold constructed for making shoes without chilled sections, and for that purpose I provide all the walls of the mold cavity with a facing of refractory material. In the drawing I have shown sections of refractory material set in the drag member and in the two members of the cope, but instead of these sections I may apply the refractory material in the form of coating sections. One section 28 of refractory material on the drag member forms the bottom wall of the mold cavity and extends from end to end thereof. Two complementary sections 29 and 30 are arranged in the cope to form the top, sides and end walls of the mold cavity.

Each of these sections 29 and 30 comprises a side wall and parts of the top wall and both end walls of the mold cavity. Thus the entire mold cavity is formed by walls 8 of refractory material and the shoe casting is protected throughout from the chilling effect of the metal in the mold. At some convenient place in the cope I provide a pouring gate 31. In the construction illustrated, the sand plug has a projection 32 to engage the top of the lug 25 to prevent the flow of metal over the top of the lug, but if it is desired to permit the metal to flow over the top of the lug, this projection may be omitted.

In practice, the mold having been opened to discharge a casting, the slideable cope member 8 is pushed into closed relation with the cope member 7 and the clamp 15 is applied to secure them together. Then the plug 20 with its suspending wires 23 therein is inserted in the opening 19 in the cope, the ends of the wires projecting well down into the mold cavity and suitably spaced apart. The attaching lug, the core for forming the opening in said lug and the reinforcing back, being assembled as a unit, are then inserted in the mold cavity through the open bottom thereof, and the ends of the wires 23 are twisted together beneath the reinforcing back to hold this assembled back unit in proper position for the casting operation. Then the drag member is swung up to closed position and secured in this position by inserting the pins 14.

My invention provides a permanent mold of simple and compact construction which can be easily operated to produce brake shoes without chilled parts. The structure of the mold is substantial and the parts are arranged for movement in opening and closing to avoid wear of the refractory facing by abrasion or otherwise in the insertion of the back unit and in the discharge of the finished casting. It is of course highly important that the refractory facing should be preserved as long as possible without undue wear so that shoes of uniform size and shape may be made without waste of material, and so that the back unit may be inserted and secured in place and the finished shoe casting discharged without deformation of said facing; and this I have accomplished in a highly satisfactory manner in my improved mold. If the shoe is not readily discharged when the mold is open, it can be easily dislodged without causing injury to the mold. If the wires are not destroyed in

the casting operation, the sand plug can be broken down to permit the discharge of the shoe, and the wires can be removed by chiseling or otherwise. The sand plug permits the escape of gases therethrough so that shoes may be cast of uniform appearance, free from deformations and blowholes.

I have illustrated the invention in a selected embodiment which I believe will be readily understood by those skilled in the art, but I do not wish to be restricted to the use of my invention for the manufacture of this particular type of brake shoe since it can be used with satisfactory results in the production of other shoes and other castings, and I consider myself entitled to make all such changes in the form, construction and arrangement of parts as fairly fall within the scope of the following claims.

I claim:

1. A permanent mold for making castings, comprising a drag and a cope having a mold cavity therein, said cope having an opening communicating with said cavity, a sand plug in said opening, the drag being bodily movable away from the cope to leave the bottom of the mold cavity open so that the parts to be embedded in the casting may be inserted in the mold cavity through the bottom thereof, means carried by said plug for suspending said parts in the mold cavity, a facing of refractory material on the drag and cope members and forming the walls of the mold cavity, and means for securing the members of the mold in closed position during the casting operation.

2. A permanent mold for making castings, comprising a drag member and a two-member cope having a mold cavity therein, said cope having an opening communicating with said cavity, a sand plug in said opening, the drag member being bodily movable away from the cope to leave the bottom of the mold cavity open so that the parts to be embedded in the casting may be inserted in the mold cavity through the bottom thereof, means carried by said plug and projecting therefrom into the mold cavity for suspending said parts in the mold cavity, a refractory facing on the drag forming the bottom wall of the mold cavity and a refractory facing on each member of the cope forming the side walls, the end walls and the top wall of the mold cavity, and means for securing the members of the mold in closed position during the casting operation.

JAMES S. THOMPSON.
